(57)

CLAIM

The ornamental design for cosmetic case, as shown and described.

DESCRIPTION

FIG. 1 is a front perspective view illustrating my design for a cosmetic case;

FIG. 2 is a front elevation view thereof;

FIG. 3 is a left side view thereof;

FIG. 4 is a top view thereof;

FIG. 5 is a right side view thereof;

FIG. 6 is a bottom view thereof;

FIG. 7 is a rear view thereof; and,

FIG. 8 is a partially open front perspective view thereof. The broken lines illustrate stitching and form part of the claimed design.
